(57) **CLAIM**

The ornamental design for a computer game simulation cockpit, as shown and described.

DESCRIPTION

FIG. 1 is a side view of a computer game simulation cockpit showing a first embodiment of my new design;

FIG. 2 is a top plan view thereof;

FIG. 3 is a first end view thereof;

FIG. 4 is a second end view thereof;

FIG. 5 is a first perspective view thereof;

FIG. 6 is a second perspective view thereof;

FIG. 7 is a side view of a computer game simulation cockpit showing a second embodiment of my new design;

FIG. 8 is a top plan view thereof;

FIG. 9 is a first end view thereof;

FIG. 10 is a second end view thereof;

FIG. 11 is a first perspective view thereof;

FIG. 12 second perspective view thereof;

FIG. 13 is a side view of a computer game simulation cockpit showing a third embodiment of my new design;

FIG. 14 is a top plan view thereof;

FIG. 15 is a first end view thereof;

FIG. 16 is a second end view thereof;

FIG. 17 is a first perspective view thereof;

FIG. 18 is a second perspective view thereof;

FIG. 19 is a side view of a computer game simulation cockpit showing a fourth embodiment of my new design;

FIG. 20 is a top plan view thereof;

FIG. 21 is a first end view thereof;

FIG. 22 is a second end view thereof;

FIG. 23 is a first perspective view thereof; and,

FIG. 24 is a second Perspective view thereof.
